UNITED STATES PATENT OFFICE.

JOHN THOMSON, OF NEW YORK, N. Y.

ELECTRIC ZINC-FURNACE WITH INTEGRAL CONDENSER.

1,086,417.

Specification of Letters Patent. Patented Feb. 10, 1914.

Application filed April 14, 1913. Serial No. 760,916.

To all whom it may concern:

Be it known that I, JOHN THOMSON, a citizen of the United States, and a resident of the borough of Manhattan of the city of New York, in the county and State of New York, have invented certain new and useful Improvements in Electric Zinc-Furnaces with Integral Condensers, of which the following is a specification, reference being made to the accompanying drawings, forming a part hereof.

This invention relates to the metallurgy of zinc having for its object the production of zinc fume which is subsequently condensed to liquid metal.

A description of the particular means for attaining the desired results and such an elucidation of the general principles applicable thereto as will provide a complete disclosure of the invention will be concurrently pointed out in connection with the description of the accompanying drawings; which represent certain embodiments of the invention.

Figure 1 is a transverse center section, as on the line A of Fig. 2, viewed in either direction; Fig. 2, from the left hand side to the longitudinal center line, B, is a one-fourth top plan view while the right hand portion is a horizontal section taken on the plane denoted by C in Fig. 1, and Fig. 3 is a detached detail modification of a portion of the condenser.

This furnace is particularly intended for the reduction of any sulfid or oxidized zinc, or lead-zinc, ores having a considerable content of gangue which is capable of being transformed or "dissolved" into a liquid slag or matte.

To avoid explanatory statements which would in fact be in the nature of repetitions, it is prefatorially set forth that this application is more or less correlated with several of the previous applications filed by the present applicant on January 2d, 1913; but reference may be particularly cited to Serial No. 739,795 thereof. This application is also related to another application (Case J), Serial No. 760,915, filed concurrently here-

with.

The decomposition of the charge is effected by heat derived by direct conduction or radiation, or by both, from compound porous bed-resistors, such as are ordinarily formed from pieces of broken carbon inter-

one of such resistors is denoted in the drawings, as D, with a pair of terminals, as 3, 4, connected to the power circuit, as E. The resistors may be energized separately, in parallel or in series. The reaction takes place at or contiguous to one of each of the vertical faces of each resistor; which may be somewhat rectangular in cross-section, the lower narrow side resting upon a refractory grating preferably built from spaced rods or bars, as 5, supported by ledges 6, above slag-sumps 7, 7^a. But the aforesaid grating, or hearth, may be formed of pierced or perforated bricks, slabs or tiles. Each resistor lies parallel to the other and they are sufficiently separated to provide space for a charging gallery, F, between them, preferably located in the center of the furnace. The gallery, or space between the opposing vertical faces of the resistors may be sub-divided by a series of longitudinal center plates, as 8, and transverse plates, as 9, forming charging pockets, H, in which the charge material, as J, is placed. The particular object of the said center plates, which are to be formed of material electrically non-conductive, is to prevent a cross-flow or shuntage of current from one resistor to the other through the charge material; and the same function is performed as to a longitudinal passage of current by the transverse plates. The bottom of the charge gallery, or of the pockets, is preferably downwardly sloped, as 10, right and left, from the center toward the grating. The condensing elements are longitudinally disposed along the outer vertical faces of the resistors and are parallel thereto.

When the charge, composed of, say, ore, or a concentrate thereof, having been suitably mixed with a reagent, and also, if required, with additional material for transforming the inert residual gangue to a liquid slag, has been supplied to the gallery or pockets that constitute charge receiving means for serving the charge to the resistor and the temperature of the charge is adequately increased by heat imparted by the resistors, the reaction proceeds; metallic fume and gases pass through the resistors in horizontal planes, as arrows a, and the inert residual—which at the moment of separation may be fluid or partially so, or an ash or sinter, or a combination of all—falls down along the vertical faces of the resistor, or of the charge material, or in spaces

between them, until arrested by the sloped bottoms. The liquid, or even "pasty", slag then flows into the lower interstices or the bottom of the resistors and from thence, 5 through the spaces, as 12, of the gratings to the sumps, as denoted by the arrows *a*, from whence it may be tapped off, as from the end openings 13, 13^a.

The particular advantages of the foregoing construction and operation are as follows, namely: The slag is being constantly evacuated from the zones of reaction, thereby neither clogging the resistors nor sealing the charge-materials, which 15 would prevent the free evolution of fume and gas; the lower sides of the resistors are effectively utilized, because of their juxtaposition, to liquefy pasty slag and keep the slag-bath sufficiently hot and fluid to be 20 readily tapped off, and if any portions of residue or charge-material in which the reaction has not been completed enters the sumps the exhaustion will be completed therein, the evolved fume and gas finding 25 exit upwardly through the grate-spaces, into the resistors and thence to the condensers. Moreover, if a zinc-lead ore is being smelted, the lead content, or a considerable portion thereof, is regainable in liquid form. In 30 such instance, the method and means here shown and described are favorable for such purpose in that lead is producible at a relatively lower temperature than that at which the free evolution of zinc-fume takes 35 place; consequently, at certain distances away from the faces of the resistors, back into the charge-material, where the temperature will be sufficient only to release and liquefy the lead, it will then percolate down 40 along the face of or through the charge and flow to the sump-baths wherein it will precipitate and be sealed from the direct radiated heat of the resistors.

Each of the fume-condensing elements is 45 formed by a plurality of vertically spaced plates disposed, as is here shown, in two series. The inner series, those contiguous to the resistor, may be of composite plates; that portion, as 14, in contact with the resistor, being of material electrically non-conductive, while the extension thereof, as 15, may be of carbon or graphite. These plates are set to form vertical spaces, as 16, into which flow the fume and gases after having 55 passed through the resistor. The said plates rest upon bricks, or a tamped facing, sloping downwardly, as 17, from the resistor, and a portion of the lower edges, as 18, of the plates project over the inner edge, 60 19, of a zinc trough or receptacle, as 20. The outer series of spaced vertical plates, as 21, are set so that their centers, as lines 22, Fig. 2, shall coincide with the centers of the spaces, as lines 23, formed by the inner 65 series of plates, the edges of the two stacks

abutting one against the other. Thus, the two sets of spaces are vertically separated or staggered. This separation may also be effected by lapping the plates, as shown in Fig. 3, or a longitudinal septum may be introduced. The result of the foregoing arrangement is that the spaces, 16, of the inner series of plates do not make direct connection with the spaces, as 24, of the outer series. The upper edges of the inner series of plates are covered with bricks, or tiles, as 25, 26. The bottoms of the outer series of plates rest in and are supported by the zinc reservoir, being immersed in the liquid metal, and a portion of their inner edges may be cut away, as 27, coinciding with the overlying portions of the inner plates. In this wise, a free space or chamber is formed, as *i*, bounded by the edges of the plates, one of the side-walls of the reservoir and the liquid metal beneath. The outer plates are stacked in a chamber, or gap, as 28, formed in the furnace and their upper ends may be flush with the top of the furnace, as 29, or they may extend beyond it, as indicated in dotted outline, 30, or again they may be shortened, as 31, leaving an open space in which may be placed a layer of filter carbon or graphite, or a layer composing heat insulating material such as carborundum as 32.

The fume and gas discharged by the resistor pass into the vertical spaces, 16, of the inner stack of plates, flowing horizontally, as arrows *a*, until meeting the edges of the outer stack of plates. Any condensed fume will run down the sides of the spaces and be collected, as arrows *n*, in the reservoir, while any remaining fume and gas also flow down upon the zinc-bath, expand in, 105 the chamber *i* and thence, as arrows *s*, pass into the spaces of the outer plates and flow upwardly, the residual gas passing to atmosphere direct as CO, or it may be burned to CO₂. Any fume condensed in the spaces of the outer plates or in the overhead filter-carbon, if such is used, will fall into the reservoir, as arrows *x*. It is to be noted that as the lower ends of the outer series of plates are immersed in the zinc-bath, their temperature will be correspondingly controlled thereat; but the upper ends of these plates, depending upon whether they are blanketed with carbon, or flush with or extending beyond the top of the furnace, 110 can be held to nearly any difference of temperature desired, or as between that of the atmosphere and of the liquid zinc in the reservoir. Furthermore, as has elsewhere been elaborated, the temperature of the zinc-bath may itself be readily controlled, as by a flue, 33, in which heat or air may be circulated.

Obviously, an additional expanding chamber may be provided at any desired portion 115

of the gap in which the outer plates are situated. So, too, any number of series of plates may be employed whereby the fume would be caused to travel up and down, 5 cross-wise, or both, in various stacks of spaces, ducts, or crevices, and the plates may be of such thickness and be so disposed as to virtually form laminated batteries. But an advantage of controlling importance is 10 derived from the arrangement shown in the drawings; for by employing stacks of vertical plates with vertical spaces the outer series of plates may at any time be cleaned and by removing the cover-bricks, 25, 26, 15 the same can also be done with the inner series of plates, the dislodged matter being collected in the reservoir from whence it can readily be raked out through suitable end-openings, not shown.

20 The condensing system just described realizes to a unique degree one of the controlling requisites for the complete and rapid condensation of fume to liquid metal, that is to say: progressive and controllable diminution of temperature from entry to exit; 25 large area of rubbing or diffusing surface; low velocity of flow and a consequent minimum of deleterious back-pressure at the reaction zone or zones.

30 This specification has purposely not been burdened with a detailed citation of the various practical conditions pertaining to igneously produced oxid of zinc, zinc blende, oxidized and silicious ores, nor to the various reagents, such as carbon, copper and iron which may be utilized; and the foregoing brief reference thereto is simply to signify that the several uses to which the present design of furnace may be adapted have 40 had due consideration.

It will doubtless be apparent that either of the longitudinal halves of the furnace, as from the center line B, Fig. 1, may be operated as a unit; or that the condensing elements may be transposed to the center and the resistors to the outside thereof. However, there are distinct advantages in compounding the resistors and condensers after the manner shown in the accompanying drawings such, say, as counterbalancing the emission of heat and that one of the resistors and its component condensing element may be examined, repaired or renewed while the other set are maintained in operation. 50 Therefore, it is to be well understood that various shifts and modifications may be made, as to which the applicant is fully cognizant, without evasion of the scope and dominant principles of the invention herein disclosed.

I claim as my invention:

1. An electric zinc furnace comprising a porous bed of carbon resistor, a means for serving charge-material to a vertical face of 65 said resistor, a condensing system disposed

along the other vertical face of said resistor, a slotted or perforated grating upon which the said resistor rests and an underlying sump which receives the non-volatilized products of the reaction.

2. In an electric zinc furnace having a porous bed of carbon resistor along a vertical face of which reacting material is served and whereat the reaction takes place, a slotted or perforated hearth or grating upon which said resistor is stacked and an underlying sump adapted to receive, from the bottom of the reaction zone, the inert or other fluidified products of the reaction.

3. In an electric zinc furnace, a sump underlying a slotted or perforated grating or hearth, upon which a porous bed of carbon resistor is supported, said sump being arranged so that the fluidified products of the reaction flow into the said sump from one side of the resistor while any fume or gas thereafter produced in the said sump passes up into and thence laterally out of the said resistor to the condensing system.

4. In an electric zinc furnace, spaced resistors along whose opposing faces the reaction is produced, the charging space or gap between the resistor being subdivided longitudinally by a wall, bricks, or slabs formed of electrically non-conductive material.

5. In an electric zinc furnace, parallel resistors along whose opposing vertical faces the reaction is produced, the charging space or gap between the resistor being subdivided longitudinally and transversely by 100 walls, bricks or slabs formed of material electrically non-conductive.

6. In an electric zinc furnace, a porous carbon resistor along one of whose vertical faces the reaction takes place, a stack of 105 vertically spaced plates contiguous to the other vertical face of said resistor, an outer stack of vertically spaced plates, each set being in staggered relation to the other, and an underlying receptacle for receiving liquid metal, whereby the vaporized products of the reaction pass into the spaces of the inner stack of plates horizontally, then deflect downwardly to the reservoir and thence pass upwardly through the spaces 110 of the outer stack.

7. In an electric zinc furnace, staggered stacks of vertically spaced plates constituting the condenser.

8. An electric furnace comprising vertically extending spaced condensing plates arranged in staggered relationship.

9. In an electric zinc furnace, stacks of vertically spaced plates, constituting the condenser, there being a barrier between the 125 spaces in one stack and the spaces in the other stack.

10. In an electric zinc furnace, stacks of vertically spaced condensing plates, the spaces in one stack vertically separated from 130

the other, the lower ends of one stack resting in a bath of liquid metal while the upper ends of the said stack at least extend nearly to the top of the furnace.

5 11. In an electric zinc furnace stacks of vertically spaced condensing plates, the spaces in one stack vertically separated from the other, portions of the lower edges of which lie above a bath of liquid metal, 10 thereby forming a free space or chamber into which the fume and gas flow from one stack enters and thence passes into the spaces of another stack.

12. In an electric zinc furnace, stacks of vertically spaced condensing plates, the spaces in one stack vertically separated from the other, one stack at least reaching nearly to the top of the furnace and another stack being covered with tiles or bricks.

20 13. In an electric zinc furnace, stacks of vertically spaced condensing plates, the spaces in the stacks being vertically separated from each other, the arrangement and construction being such that all of the 25 spaces may be examined and cleaned from above, the dislodged material being collected in an underlying reservoir.

14. In an electric zinc furnace, stacks of vertically spaced condensing plates, portions 30 of one stack contiguous to a resistor being formed of electrically non-conductive material.

15. In an electric zinc furnace, parallel porous resistors embracing a plurality of 35 charge receiving means, the reaction taking place along the opposing vertical faces of said resistors which rest upon slotted or perforated hearths, sumps beneath the said hearths for receiving liquid residue from 40 the bottoms of the reaction zones, and condensing systems, disposed along the outer parallel faces of said resistors, said condensing systems comprising stacks of vertically spaced plates, the spaces in one stack 45 separated from another, the condensed fume being collected in reservoirs beneath the stacks and the residual gases passing vertically therefrom into spaces in the outer stacks and finally passing to the atmosphere.

50 16. In an electric zinc furnace, having vertically spaced condensing plates, the spaces

in one stack being vertically separated from the spaces in the other stack, the furnace being constructed so that the temperature of the lower ends of an outer stack is controlled 55 by a bath of liquid metal and so that the temperature of the upper ends of said stack can be manually controlled.

17. In an electric zinc furnace, an integral condensing system, a porous resistor 60 resting upon a slotted or perforated hearth, a sump beneath the said hearth and charge receiving means opposite to a face of said resistor, the reaction taking place in a zone at and back from the vertical face thereof, 65 whereby when a metal, such as lead, is liberated at a relatively low temperature it may percolate down along the face or through the ore-charge thence flowing into the aforesaid sump. 70

18. An electric furnace comprising a broken carbon resistor supported on a grate above an underlying sump, the charge receiving space having a supporting surface which slopes toward the sump whereby 75 fluidified products of the reaction will be caused to flow into the sump.

19. An electric furnace comprising a bed of carbon which is located over a sump, the furnace being provided with a charge receiving portion at one side of the resistor and a condensing system at the other side of the resistor, the sump being arranged so that there is communication between it and the condensing system only by passing through the 85 resistor. 80

20. A combined zinc furnace and condenser comprising a resistor, a sump arranged to receive fluidified products of the reaction which takes place at one side of the resistor, 90 a condensing system arranged at the other side of the resistor and a sump at the lower part of the condensing system for receiving liquefied zinc resulting from the condensation of the zinc fumes. 95

This specification signed and witnessed this 12th day of April, 1913.

JOHN THOMSON.
